FLUSH VALVE

Edward F. Both, Union City, N. J.

Application June 20, 1949, Serial No. 100,253

2 Claims. (Cl. 137—652)

1

This invention relates to valves and has more particular reference to flush valves of the type that are maintained closed by fluid pressure and reclose themselves automatically after manual actuation to open position.

Valves of this type, while not new in principle, have generally been quite complicated in design. The complicated nature of these valves, therefore, made them quite expensive and difficult to manufacture.

In general, therefore, it is an object of the present invention to provide an improved type of flush valve which features ruggedness and simplicity of design together with ease of manufacture so that it can be made available at relatively low cost.

Another object of this invention resides in the provision of a flush valve of the character described which will operate with high efficiency and over long periods of time because of its simple and rugged construction.

With the above and other objects in view which will appear as the description proceeds, this invention resides in the novel construction, combination and arrangement of parts substantially as hereinafter described, and more particularly defined by the appended claims, it being understood that such changes in the precise embodiment of the hereindisclosed invention may be made as come within the scope of the claims.

The accompanying drawing illustrates one complete example of the physical embodiment of the invention constructed in accordance with the best mode so far devised for the practical application of the principles thereof, and in which:

Figure 1 is a vertical sectional view through the valve of this invention illustrating the interior construction thereof and the valve in closed position;

Figure 2 is a view similar to Figure 1 showing the valve actuated to open position; and

Figure 3 is a view similar to Figure 2 showing the valve in a partially closed position and illustrating the manner in which fluid pressure effects closure of the valve.

Referring particularly to the accompanying drawings in which like numerals indicate like parts, the valve of this invention comprises a valve body 5 including an upright cylindrical main body portion 6, a cylindrical cap portion 7 disposed over the main body portion 6 and a clamping ring 8 for holding the cap portion 7 on the top of the main body portion 6 and coaxial therewith.

The upper end of the main body portion 6 is turned down to provide a short axial pilot or neck

9 which projects upwardly into a shallow well 10 in the underside of the cap portion 7 and which has a diameter to snugly receive the neck or pilot 9. A suitable gasket 11 in the bottom of the well 10 is preferably employed to preclude leakage around the rim of the cap at the joint between it and the main body portion 6.

The cap portion 7 has a diameter slightly less than that of the body portion 6 but at its lower end has an annular flange 13 thereon over which the connecting ring 8 engages, and inasmuch as the interior of the ring is provided with screw threads to engage corresponding screw threads on the exterior of the main body portion 6 it will be apparent that the cap portion 7 is drawn tightly down onto the outer end of the neck or pilot 9 to compress the gasket 11 therebetween upon tightening of the ring 8.

The main body portion 6 has an axial bore 15 leading upwardly thereinto from the bottom to provide an outlet passage for the valve, and this bore aligns with and leads into the lower or inner end of a counterbore providing an upright main valve chamber 16 larger in diameter than the bore 15 and opening to the top of the main body portion. At the inner end of the counterbore, that is, at its junction with the bore 15, the main body portion is provided with a valve seat 17 with which a valve plug 18 engages to close the outlet passage and shut off communication between it and a fluid inlet passage 19 formed by a bore extending into one side of the main body portion and leading into the lower end of the main valve chamber 16.

The valve plug 18 is formed on the lower end of a valve element 20 which has an enlarged cylindrical piston-like head 21 at its upper end slidably fitting the upper end portion of the main valve chamber. The plug 18 and head 21 are connected by means of an axial reduced neck 22 extending from the underside 23 of the head and joining with the small diameter end of a frusto-conical formation or surface 24 on the plug.

When the inlet passage 19 is connected with the source of fluid under pressure the fluid acts upon the frusto-conical surface 24 of the plug with a downward force tending to hold the plug seated in its valve closed position, but the downward force of the fluid upon the plug is less than the upward force which the fluid exerts upon the underside 23 of the enlarged head 21 of the valve element. Hence it will be seen that the pressure of fluid in the inlet passage 19 is capable of acting upon the enlarged head 21 to lift the valve element so as to establish communication between

the inlet and outlet passages for flushing purposes.

Since fluid under pressure in the inlet passage 19 tends to unseat the valve and open the same it will be apparent that the valve can be maintained closed only when the fluid from the source can exert a greater downward force upon the valve element than the upward force which it exerts upon the surface 23 of the enlarged head on the element. To this end provision is made for subjecting the upper end of the main valve chamber 16 to the pressure of fluid in the inlet passage 19. Generally this is accomplished by fluid branch passages which lead from the inlet and outlet passages upwardly into the cap portion 7 of the body and downwardly into the upper end of the main valve chamber.

One of these fluid passages 26 comprises a relatively small diameter tube 27 which is pressed in a vertical hole extending downwardly from the top of the main body portion 6 into the inlet passage 19, between the inlet end of the passage 19 and the main valve chamber 16. In order to insure that fluid under pressure will flow upwardly into the branch passage 26 when the main valve is open, the side portion 28 of the tube adjacent to the main valve chamber is extended downwardly a distance into the inlet passage to provide in effect a scoop or deflector.

The upper end of the branch passage 26 is in register with a hole 30 in the underside of the cap portion 7 leading into the inlet end of a cylinder-like auxiliary valve chamber 31 disposed horizontally in the cap portion substantially crosswise over the upper end of the main valve chamber. The auxiliary valve chamber 31 is readily provided by boring into the side of the cap portion 7 to a distance slightly beyond the center or axis of the main valve chamber 16, and the outer end of this bore is sealed as by 40 threading a plug 32 thereinto.

At the inner end of the auxiliary valve chamber 31 the underside of the cap portion 7 is provided with a port 33 which communicates the upper end of the main valve chamber with the side of the auxiliary valve chamber to thus allow fluid to flow upwardly through the branch passage 26 and inwardly in the auxiliary chamber 31, through the port 33 and into the upper end of the main valve chamber so as to subject the top side 34 of the head 21 of the valve element to the pressure of the fluid in the inlet passage 19.

Since the surface 34 on the head is larger than the undersurface 23 thereof it follows that the total downward force acting on the valve element will be in excess of the upward component and the valve element will be held in its lowermost position by the fluid to keep the plug portion 18 engaged with its seat 17.

Actually the downward force on the surface 34 of the valve element is added to the force the fluid exerts on the frusto-conical surface 24 of the plug portion to greatly exceed the upward force on the undersurface 23 of the enlarged head.

Inasmuch as the valve element is securely maintained in its closed position by the pressure of fluid in the inlet passage 19 and in the upper end of the main valve chamber 16, it will be apparent that it is necessary to relieve the pressure in the upper end of the main valve chamber to enable opening of the valve by the force of fluid acting on the undersurface 23 of the enlarged head 21.

This is accomplished by the inward manual 75

depression of an actuating stem 36 connecting with a piston-like auxiliary valve or plunger 37 slidable in the auxiliary valve chamber 31. The valve element 37 is responsive to the pressure of fluid conducted into the inlet end of the auxiliary valve chamber through the branch passage 26 and is normally held by this fluid pressure in the opposite or discharge end of the auxiliary valve chamber. In this position, the auxiliary valve 10 closes a port 38 connecting the discharge end of the auxiliary chamber with a branch "relief" passage 39 leading to the outlet passage 15. The relief passage 39 is formed jointly by registering vertical holes drilled upwardly into the underside 15 of the cap portion and downwardly into the top of the main body portion 6, substantially diametrically opposite from the branch passage 26.

The lower end of this relief passage 39 communicates with the outlet passageway 15 through 20 an angle passageway 39' drilled into the side of the main body portion and having its outer end plugged as at 40.

As will be readily understood, the stem or actuator 36 of the auxiliary valve projects 25 through a packing gland arrangement 41 on the side of the cap 7 to prevent the leakage of fluid past the stem.

Closure of the port 38 is effected by a frusto-conical surface 43 on the auxiliary valve 37 which 30 has its small diameter end arranged to enter the port 38 a slight distance for this purpose. Hence, in the position of the parts illustrated in Figure 1, fluid pressure acts directly upon the surface 24 of the valve plug and upon the flat top surface 34 of the enlarged head on the main valve element to hold it closed.

The main valve element, of course, is opened by fluid pressure whenever the plunger 36 is depressed inwardly as seen in Figure 2 to shut off the upper end of the main valve chamber from the branch passage 26 leading to the inlet passage, and to establish communication between the upper end of the main valve chamber 16 and the outlet port 15 through the ports 33 and 38 and the relief passages 39 and 39'.

As stated previously, inward depression of the auxiliary valve in this manner relieves the pressure in the upper end of the main valve chamber so that the pressure of fluid acting on the undersurface 23 of the valve element lifts the same off of its seat, as shown in Figure 2, to enable fluid to flow through the valve from the inlet to the outlet passages thereof.

In order to effect opening of the valve in this manner it is only necessary to push the actuator 55 36 inwardly and the auxiliary valve may be held so depressed for any desired length of time to maintain the valve in open condition. In ordinary use of the valve, however, the auxiliary valve 37 is only momentarily actuated and the main valve element is adapted to be automatically reclosed by the pressure of fluid acting on the top of the head on the valve.

Reclosure of the main valve by fluid pressure, however, is not instantaneous and is delayed for a time interval determined by the setting of a metering needle valve 45 threaded into the cap portion 7 in line with the branch passage 26 and having its pointed lower end arranged to adjustably restrict the flow of fluid into the inlet of the auxiliary valve chamber. Hence, after momentary depression of the actuator 36 to open the main valve, fluid entering the inlet passage is deflected upwardly into the branch passage 26 and flows into the inlet of the auxiliary valve

chamber at a rate depending upon the setting of the needle valve to slowly shift the auxiliary valve to its position closing the port 38 and establishing communication between the inlet passage and the upper end of the main valve chamber to again cause the pressure to build up therein for reclosure of the valve.

The time it takes for reclosure of the main valve is also partly determined by the sizes of relatively narrow longitudinal and circumferential grooves 47 and 48, respectively, in the exterior of the auxiliary valve 37 which in effect form a partial by-pass around the valve and allow fluid entering the inlet of the auxiliary valve chamber to flow part way therewith and through the port 33 into the upper end of the main valve chamber to slowly build up the pressure therein.

In this manner the force exerted against the undersurface 23 on the enlarged head of the main valve element is slowly overcome during reclosure of the valve, as seen in Figure 3, by the increasing pressure being built up in the upper end of the main valve chamber and reacting with an increasing downward force upon the top of the valve element.

Each time the plunger or actuator 36 is momentarily depressed, therefore, a more or less predetermined volume of fluid will flow through the valve and the valve will be automatically released after a time interval depending upon the adjustment of the needle valve 45. If a lesser volume of fluid is to be delivered through the valve the needle valve may be backed up on its threads to lift its lower end to a position less restricting the flow of fluid into the inlet end of the auxiliary valve chamber so as to cause quicker pressure response of the auxiliary valve 37 and its closing of the port 38. This effects earlier registry of the circumferential groove 48 with the port 33, and obviously speeds the downward closing motion of the main valve.

To effect an increase in the volume of fluid to be passed through the valve, the needle valve is turned inwardly on its threads to advance its lower pointed end downwardly into the branch passageway 26 to further restrict the flow of fluid into the inlet of the auxiliary valve chamber. This has the effect of delaying response of the auxiliary valve 37 to the pressure of fluid delivered into the auxiliary valve chamber, accordingly delaying the building up of pressure in the upper end of the main valve chamber.

From the foregoing description taken in connection with the accompanying drawings it will be readily apparent to those skilled in the art that the arrangement of valve elements and passages in the valve of this invention produces an exceptionally simple and rugged construction which is particularly easy to manufacture and may be made available at relatively low cost; and that these advantages are assured without sacrificing efficiency of operation and long life of the structure.

What I claim as my invention is:

1. In a flush valve of the type having a body provided with inlet and outlet passages opening into an upright main valve chamber, and a vertically movable main valve in said main valve

chamber movable upwardly by the pressure of fluid in the inlet passage from a valve closed position to a valve open position communicating the inlet and outlet passages, said body having branch passages one of which communicates with the inlet passage and the other with the outlet passage: means on the body defining a cylinder-like release valve chamber communicated at one end with the inlet branch passage, the outlet branch passage communicating with the opposite end of the release valve chamber, coaxially thereof; means on the body providing a communicating passageway between the upper end of the main valve chamber and the cylinder-like release valve chamber at a location remote from the inlet end of said release valve chamber; a piston provided a release valve at all times entirely within the release valve chamber and slidably fitting the same, said piston at all times being free to move in its chamber in response to the pressure of fluid in the inlet end thereof toward said opposite end of the release valve chamber to a normally inoperative position closing off the outlet branch passage from the release valve chamber and the upper end of the main valve chamber; means on said piston providing a restricted by-pass around the piston in said inoperative position thereof, said by-pass leading from the inlet end of the release valve chamber to the upper end of the main valve chamber through said communicating passageway so that the main valve will be held down in its valve closed position by the pressure of fluid above the main valve; and means for manually moving said piston toward the inlet end of said release valve chamber to an operative main valve releasing position simultaneously closing off communication between the inlet end of the release valve chamber and the upper end of the main valve chamber and establishing communication between the upper end of the main valve chamber and the outlet branch passage.

2. The flush valve set forth in claim 1 wherein said by-pass around the piston comprises an annular groove in the periphery of the piston aligning with the communicating passageway between said chambers only in the inoperative position of the piston, and a longitudinal groove in the periphery of the piston leading from said annular groove to the end of the piston adjacent to the inlet end of the release valve chamber.
